UNITED STATES PATENT OFFICE.

CHARLES KING, OF GRAND RAPIDS, MICHIGAN, ASSIGNOR OF ONE-HALF
TO WALTER E. MOORE, OF SAME PLACE.

CARPET-SWEEPER.

SPECIFICATION forming part of Letters Patent No. 616,870, dated December 27, 1898.

Application filed May 17, 1898. Serial No. 680,976. (No model.)

To all whom it may concern:

Be it known that I, CHARLES KING, a citizen of the United States, residing at Grand Rapids, in the county of Kent and State of Michigan, have invented certain new and useful Improvements in Carpet-Sweepers, of which the following is a specification.

My invention relates to improvements in carpet-sweepers having automatic pan action; and its objects are, first, to insure a positive uniform pan action from the motion of the handle of the sweeper; second, to so support the pans for automatic action that each pan is acted upon independent of the other; third, to support the pans each independent of the case upon a single actuating-bar and a single actuating-spring at each end of the pan; fourth, to provide an auxiliary means of carrying the pans nearer the floor or carpet than they can approach by the automatic action from the handle; fifth, to insure uniform movement at both ends of the pan, and, sixth, to provide against the necessity of using staples, &c., to support the auxiliary adjusting-springs in the case. I attain these objects by the mechanism illustrated in the accompanying drawings, in which—

Figure 1 is a sectional perspective of my sweeper on the line xx of Fig. 2. Fig. 2 is a 30 sectional elevation of the same on the line yy of Fig. 3; and Fig. 3 is a partial end elevation of the same, showing the position in outline of the auxiliary adjusting spring or rod that supports the wheels.

Similar letters refer to similar parts throughout the several views.

A represents the sweeper-case.

B is the dust-pan.

C is the rod that supports and actuates the 40 inner edges of the pans.

In Fig. 1 I have shown one pan removed and the other in place to more plainly illustrate the manner of connecting the actuating-rods C with the actuating-levers D and the 45 pans. The ends of the actuating-rods are bent at right angles to form the bearings d' and d'' , one of which passes through an aperture in the lever D, and the other passes through a corresponding aperture in the end

of the pan. The angle-levers D are pivoted 50 to the ends of the case, as at d, so that the throwing of the free end around, as indicated by the dotted lines to the left in Fig. 1, will carry the angle of the lever, and with it the actuating-rod, down from the top of the case, 55 and by this means the inner edge of the pan is carried toward the floor.

The pan and actuating-rods are held to normal position by the springs F, which are securely attached at one end to the ends of 60 the case and are pivotally attached at the other end to the pan by means of the right-angle bearing f, passing through an aperture in the pan between the point of contact of the actuating-rods and the outer edge of the 65 pan, so that its tensile force draws the pan up to a bearing at one edge with the actuating-rods and at the other end in the rabbeted bearing a at the edge of the side of the case, this being the only vertical support that is 70 provided for the pans. It is to be understood that there is an actuating-rod and a supporting-spring at each end of each pan, so that the pans are supported alike at both ends. For placing the actuating-rods I run 75 a saw-kerf c in the ends of the case of sufficient depth and width to admit the full size of the rod, so that the rods are wholly secured against lateral movement. By this means the pans are held against lateral motion, so that the automatic working of the inner edges is pivoted from the bearing a on the side of the case, and the dumping motion is pivoted from the bearing d'' on the actuating-rods, and their return to their normal position is insured by the rebound of the springs F, as hereinbefore suggested.

The angle-levers D are actuated by the lateral or swinging motion of the arms g on the equalizing-rod G in following manner: The 90 equalizing-rod G is revolvably secured to the top of the case, as by means of the supports g'' , and extends the entire length of the inside of the case. At the ends of the case they are bent down at right angles to form the 95 arms g, which extend down to the slot h', where it is bent out at right angles with the arms g and passes through the end of the case

and far enough beyond to pass into and act as a pivotal support for the handle-bow H, as at g' and h. The slot is made sufficiently long to give ample swing to the bearing g' to 5 carry the levers D over far enough to give the inner edges of the pans the desired vertical motion, so that the drawing and pushing of the handle in manipulating the sweeper will alternately throw the inner edges of the 10 pans to the floor and the rebound of the springs F will return them, and with them the levers D, to their normal position.

The springs F are held to place by the staples f'' and the end f', which latter is bedded 15 in a saw-kerf in the end of the case, as shown in Fig. 1.

The equalizing-rod G must be of sufficient 20 rigidity to insure a uniform motion at both bearings of the handle-bow, so that there will be no possibility of one end of the bow moving and the other standing rigid or one end 25 moving one way and the other end moving the other way, as often happens in turning the sweeper while in operation when this equalizing-bar is not applied to the sweeper.

While the automatic action of my sweeper is sufficient for all practical purposes on carpets, I find that by adding an auxiliary feature to this end I am enabled to use the 30 sweeper successfully on polished floors, linoleum, and even on tile floors; but it is of course necessary to drop them a trifle lower than it is desirable to drop them for carpet-sweeping, and for this purpose I form my 35 axletrees or wheel-supports upon a spring-bearing, so that a slight pressure upon the handle H will force the case, brush, and pans still closer to the floor.

I construct both axletrees e on a single and 40 continuous rod E, as follows: The axletrees e pass out through the ends of the case, and at the inner surface they are bent at right angles and extend from the apertures K, which are considerably larger, diametrically, than the 45 axletrees, so that the axletrees may have free vertical motion, to the line of angle E' of the side of the case. From here it is bent to lie along this line to near the center of the case, forming torsion-springs of sufficient strength 50 to easily support the case and its attachments. From these points it bends again at right angles and extends up along the surface of the inclined portion of the case until it reaches the upper angle-line E'', along which 55 it lies, forming a continuous bearing of such peculiar form that its tensile force holds it to place without the necessity of using staples or other means of securing it, thus rendering it much more convenient, less laborious, and less 60 expensive than those in ordinary use. The several bends and bearings of this axle-tree attachment may be readily traced through the aid of the reference-letters e, e', e'', e''', and e'''', consecutively.

Having thus fully described my invention, 65 what I claim as new, and desire to secure by Letters Patent of the United States, is—

1. In a carpet-sweeper, a case, pans and wheels; in combination with an equalizing-rod revolvably secured to the top of the case, 70 the ends bent down and out through the ends of the case and engaging the handle-bow as a swinging support and equalizing-bar therefor, substantially as, and for the purpose set forth.

2. In a carpet-sweeper, a case, pans, wheels and brush; in combination with an equalizing-bar secured longitudinal of the inner surface of the top of the case, and the ends bent down, and out through slots in the ends of the 80 case to form a swinging and equalizing support for the handle-bow, angle-levers pivoted within the case in position to be actuated by said support, connecting-rods between said angle-levers and the ends of the pans, the 85 ends of the case grooved to hold said connecting-rods, springs secured to the ends of the case with their free ends pivotally connected with the ends of the pans between the connecting-rods and the outer edge of the pans, 90 said springs arranged to return the pans to normal position both from the dropping of the inner edge and the dumping of the outer edge, substantially as and for the purpose set forth.

3. In combination with the case, wheels, 95 brush and pans of a carpet-sweeper, an equalizing-bar revolvably secured to the case, the ends projecting down and out through slots in the ends of the case to position to engage the hubs of the handle-bow and form swinging 100 pivotal bearings therefor, actuating levers and rods connecting said swinging arm with the ends of the pans to cause them to reciprocate vertically, and springs for returning and holding the pans to normal position, 105 substantially as and for the purpose set forth.

4. In combination, the case, brush, wheels and pans of a carpet-sweeper; with an equalizing-bar revolvably attached to the top of the case within, arms projecting down, thence out through slots in the ends of the case and engaging the hubs of the handle-bow to form a swinging pivotal support therefor, actuating levers and rods connecting the swinging arm 110 of the equalizing-bar with the pans to actuate 115 the inner edges thereof, appliances for returning and holding the pans to normal position, and torsion-spring axletrees for the wheels, substantially as and for the purpose set forth.

5. In a carpet-sweeper, the case, pans, brush and wheels; in combination with axletrees formed of a single wire for each pair of wheels, said wire having a straight portion at the center that lies along the upper angle-line of the case, thence, at each side, bending down and extending to the lower angle-line of the case, thence bending out and both portions lying 120 along the said lower angle-line of the case and 125

forming a torsion-spring, to the ends of the case, thence bending at right angles with said spring and at an acute angle with the first-mentioned arms, and extending to openings 5 through the ends of the case, and thence bent at right angles and passing through said openings and to position to receive the wheels, all being so formed that it will retain its position in the case and permit of the vertical adjust-

ment of the case, substantially as and for the purpose set forth.

Signed at Grand Rapids, Michigan, May 12, 1898.

CHARLES KING.

In presence of—

ITHIEL J. CILLEY,
JAS. M. CARVER.
